UNITED STATES PATENT OFFICE.

EDMUND C. MORGAN, OF CHICAGO, ILLINOIS.

MINING AND LOADING MACHINE.

1,271,198.

Specification of Letters Patent.

Patented July 2, 1918.

Original application filed November 10, 1896, Serial No. 611,603. Divided and this application filed February 10, 1911. Serial No. 607,753.

To all whom it may concern:

Be it known that I, EDMUND C. MORGAN, a citizen of the United States, residing at Chicago, in the county of Cook and State 5 of Illinois, have invented certain new and useful Improvements in Mining and Loading Machines, of which the following is a specification.

This application is a division of my application Serial No. 611,603, filed in the United States Patent Office November 10, 1896, granted November 3, 1914, No. 1,116,356 and to which application reference may be had for an understanding of the parts not specifically described herein.

More particularly the present invention relates to improvements in machines for scooping and loading materials which are loose or which may be dislodged or loosened. 20 A further object is to provide an improved machine of this character having means whereby the loosened material may be scooped up and delivered to a conveyer to be conveyed away, a further object being the provision of means whereby the scooping mechanism and the conveying mechanism may be controlled at will.

A further object is to provide an improved machine of this character embodying a scoop 30 having means operating in conjunction therewith for cutting the material to be excavated.

A further object is to provide an improved machine of this character which will be simple, durable and cheap in construction, and effective and efficient in operation.

To the attainment of these ends and the accomplishment of other new and useful objects, as will appear, the invention consists 40 in the features of novelty in the construction, combination and arrangement of the several parts hereinafter more fully described and claimed in connection with the accompanying drawings and as more particularly set forth in the claims.

In the accompanying drawings illustrating an exemplification of the invention, Figure 1 is a general top plan view, partly in section and with parts broken away, of 50 an improved machine of this character constructed in accordance with the principles of this invention.

Fig. 2 is a vertical longitudinal sectional view taken on line 2—2, Fig. 1.

Fig. 3 is an enlarged detail sectional view 55 taken on line 3—3, Fig. 2.

Fig. 4 is a detail sectional view taken on line 4—4, Fig. 2.

Fig. 5 is a detail sectional view taken on line 5—5, Fig. 1.

Fig. 6 is a plan view of the construction and arrangement shown in Fig. 7.

Fig. 7 is a detached detail view in side elevation of another form of mechanism for loading the material into the car. 65

Fig. 8 is a detached detail view in side elevation illustrating an arrangement for automatically cutting or snubbing or enlarging the cut made by the cutter preparatory to breaking down the under-cut material. 70

Fig. 9 is a view in detail showing the gearing for moving the scoop carrying frame backward and forward.

Referring more particularly to the drawings, and in the present exemplification of the invention, the numeral 15 designates generally the frame work upon which the mechanism is mounted and this framework may be of any suitable size and configuration as 80 to properly accommodate the several parts of the apparatus and to permit of the free and ready operation of the apparatus. The framework is preferably made portable by being mounted upon suitable traction wheels 85 16 as shown more clearly in Fig. 2, whereby the machine may be readily advanced to its work or retracted therefrom and may be transported from one place to another. These traction wheels may be positively propelled in any desired, suitable, or convenient manner or by any suitably arranged mechanism adapted to such purpose. 90

Suitably mounted upon the frame work of the machine is a motor 17 arranged and 95 adapted to operate the several mechanisms hereinafter to be referred to and as will be more fully described, and this motor may be of any suitable or convenient type of motor adapted to the purposes required. In the 100 form shown and as merely illustrative of an operative means, the motor comprises an electric motor, the current being supplied thereto through a suitable electric conductor 18, as will hereinafter be more fully explained.

A gear 19 connected with the motor to be driven thereby is arranged to engage and

drive a gear 20 mounted on a shaft 21 preferably arranged to extend transversely across the machine and which has connected therewith for rotation thereby gears 22 (see Figs. 1 and 3) by which, through sprocket or other suitable form of gearing 23, the traction wheels 16 are driven.

Any suitable, well known form or arrangement of clutch 24 may be employed for throwing the driving gear of the traction wheels into and out of operation at will, and this clutch may be controlled by a suitable operating lever 25, which latter is located so as to be readily accessible, as shown more clearly in Figs. 1 and 3. By suitably actuating or reversing the motor, the traction wheels may be driven in any desired direction to advance the machine to its work or to withdraw the same or to transport the machine from one place to another, and by suitably manipulating the clutch 24 through the medium of the lever 25, the driving gearing of the traction wheels may be thrown into or out of action. It will be understood that by means of the traction wheels, the machine is only fed up to the work and in the present exemplification of the invention where cutters are shown for cutting the wall of the material, the machine is only fed up to the point where the cutters, hereinafter to be described, are ready to begin to cut the material, for, obviously, the resistance offered to the cutter during the operation thereof on the material would be too great to be overcome by the traction wheels. When this point is reached, therefore, it becomes important and necessary to brace the machine against the resistance offered by the material to be cut, and to provide means for advancing the cutter into the material. In order to accomplish this purpose, there is mounted upon the frame 15 in any suitable and convenient manner a pair of screw rods 26, one preferably on each side of the machine, and each being pivoted at one end thereof to a pair of arms 27, in toggle joint fashion, each arm being in turn pivotally connected to an anchor shoe 28, the members of each of the shoes 28 being, if desired, suitably serrated on their engaging faces, and respectively arranged to engage the floor and roof of the walls of the room, as clearly shown in Fig. 2. From this construction and arrangement it will be seen that when endwise pressure is exerted upon the screw rods 26, in a direction away from the point where the cutter is operating, the toggle arms 27 will be operated to force the anchor shoes 28 away from each other and into engagement with the floor and roof of the room respectively, thereby securing and firmly anchoring the entire machine. If pressure is continued to be exerted longitudinally of the screw rods 26, the machine will be advanced or fed forwardly away from

the anchor shoes and in a direction to advance the cutter into the material. In practice, when the anchor shoes are arranged to engage the floor and roof of the room it is preferable to provide two or more of these screw rods and hence, also, two or more pairs of toggle arms 27, and shoes 28 for the reason that by suitably arranging one pair of these anchoring and feeding devices on each side of the machine and another pair on the opposite side, as clearly indicated in Fig. 1, it is possible to straighten the machine in case its feed departs from a straight line. This may be easily accomplished by throwing the one or the other of the anchoring and feeding devices into or out of action, as occasion may require. Any suitable mechanism may be provided for exerting the pressure above mentioned longitudinally upon the screw rods 26 whereby the machine is first anchored and then fed forwardly to advance the cutter to its work. A simple and efficient means for accomplishing this result will now be described, and comprises a gear 29 arranged to be driven from the motor 17 and to engage and drive a train of gears 30, 31. The gear is mounted to rotate with and adapted to drive a shaft 32 suitably mounted in the frame of the machine. A shaft 33 is suitably mounted in the frame of the machine to extend transversely thereacross and carries a gear 34, arranged to engage a suitable gear 35 on the shaft 32.

An internal screw threaded sleeve or nut 36 (shown more clearly in Fig. 2) is mounted on each of the screw rods 26. By rotating said nuts or sleeves in one direction or the other, the desired pressure is exerted upon the screw rods 26 in one direction or the other to effect an anchoring of the machine and the feed thereof, or else, to effect a release of the machine. As the arrangement of the gearing for rotating these nuts is the same for all of the screw rods 26, a specific description of the arrangement and operation of one will apply equally as well to them all. The nut 36 carries or has formed integrally therewith two gears 37, 38. Upon a suitably and conveniently mounted short or stub shaft 39 (see Fig. 1), two gears 40, 41, are mounted said gear 41 being preferably of a relatively large diameter and meshes directly with the gear 38 of the nut 36 while the gear 40 is of relatively small diameter and engages and drives the gear 37 through an intermediate idler gear 42. From this construction it will be manifest that when the gear 41 is idle and the gear 40 acting, the sleeve 36 will be slowly rotated in one direction, that is, in a direction to effect a longitudinal pressure on the screw rod 26 in a direction to cause the anchor shoes 28 to grip the roof and floor or side walls of the room and to effect a feeding of the ma-

chine forwardly, while if the gear 40 is idle and the gear 41 acting, said sleeve 36 will be rapidly revolved in the opposite direction, and an endwise movement of the screw rod 5 26 in the opposite direction will be effected, thereby releasing the anchor shoes 28. Any suitable or well known form of clutch 43 (see Figs. 1 and 2) may be employed to throw either gear 40, 41, into or out of action at will. A gear 44 mounted on shaft 39 is arranged to engage a gear 45 on the shaft 33, whereby the train of gearing above referred to may be driven. By means of a 10 suitably and conveniently arranged clutch 15 46 the mechanism for actuating the anchoring and feeding mechanism on one side or the other of the machine may be thrown into or out of action at will. From the foregoing description it will be manifest that when the 20 cutter is advanced to the limit of the screw rods 26 by suitably manipulating the clutch 43, the screws may be moved in the opposite direction to advance the anchoring shoes to a point closer to the machine, thereby affording a fresh grip, when the feeding action may be repeated.

The cutting mechanism and the means for actuating the same, according to this exemplification of the invention, will now be described. In practice it has been found desirable to use the ordinary sprocket chain cutters. Upon the front end of the framework 15 there is mounted a cutter frame designated generally by the reference numeral 47 (see particularly Figs. 2 and 8), in such relation that the chain cutter 48 (see also Fig. 1) mounted to operate thereon will operate in a horizontal plane to under-cut the wall of the material or to cut what might 30 be termed the floor kerf as clearly indicated in the figures referred to. The cutter frame 47 may be supported in any suitable manner, preferably by means of the bottom of the supporting frame 15, and any of the usual, well known types of sprocket chain cutters employed in the art may be used. This 40 chain cutter 48 is preferably actuated from the shaft 32 through the medium of a gear 49 mounted on said shaft (see particularly Fig. 2) to engage and drive a gear 50 mounted on an upright shaft 51, which latter is suitably mounted in the frame work and carries a sprocket gear 52 arranged to engage and drive the chain cutter 48. The shaft 51 may 50 be thrown into or out of operation at will by means of any suitable, convenient, or well known form of clutch 53 carried by the shaft 32. The horizontal cutters 48 are preferably arranged to cut a kerf extending substantially the entire width of the room so that as the machine advances farther and farther into the vein or wall of the material, the cutter cuts all the way across to form the floor for the room. In order to cut the 60 side walls of the room at the same time and in order to facilitate the breaking down of the material, thereby after breaking down the material leaving the side walls smooth and regular to permit the machine to advance, side cutters 54, 55, are provided and 65 arranged to operate in upright planes, and a suitable frame 56 is provided upon which the side cutters operate. These side cutters may be actuated preferably by means of a short horizontal shaft 57 (see Fig. 1) which 70 carries a suitable sprocket at the outer end thereof over which the side cutter chain 54 runs and at the inner end of said shaft is a gear 58 arranged to engage a gear 59 carried by the shaft 51 (see Fig. 2). From this construction it will be manifest that when the shaft 51 is rotated the side cutter 54 will 75 also be actuated. A similar arrangement is provided on the opposite side of the machine for actuating the side cutter 55, except that 80 in this instance the upright shaft 60 corresponding with the shaft 51 is rotated by the movement of the horizontal chain cutter 48, said chain cutter engaging a sprocket gear on the upright shaft 60, and thereby 85 rotating said shaft, and hence, through the engagement of the gears 61, 62, effecting a rotation of a short horizontal shaft 63, corresponding to the shaft 57, and which carries a sprocket chain over which the side cutter 55 passes. In order to withdraw the cutters from the kerf in which they are operating, that is, when it is desirable or necessary, for instance, to withdraw the entire 90 machine from the room in which it is operating, and also, for the purpose of facilitating the transportation of the machine from place to place or point to point, it is desirable to make provision for so collapsing the cutters that undue friction against the walls 95 of the kerf in case of the horizontal cutter, or of the walls of the kerf and room in the case 8 the side cutters, will not be opposed to the ready or easy withdrawal of the machine. In order to accomplish this, the 100 frames 47 and 56 upon which the cutters operate are constructed in sections, the adjacent sections being secured together by suitable fastening devices adapted to be readily removed to permit removal of the frame sections.

In the operation of mining the material, in the form of the invention shown herein, after the cutters have been advanced to the desired depth of cut, it has heretofore been 105 the custom to withdraw the machine in order to effect a breaking down of the undercut body of the material. This necessitated an arresting of the action of the machine for a considerable time to withdraw it and again advance it to the work. In the present invention there is provided means whereby the withdrawal of the machine is unnecessary during the breaking down operation, which will now be described.

Journalized in the framework of the machine is a shaft 64 arranged to extend transversely across the machine, which shaft carries a gear 65 arranged to mesh with and be driven from a gear 66 (see Fig. 1) carried by the shaft 51, and by means of which rotation is imparted to the shaft 64. By means of any ordinary and well known form of clutch 67, the rotation of the shaft 64 may be arrested or effected at will. A shield 68 preferably extending entirely across the machine is journaled to swing upon the shaft 64 (see also Fig. 2) and carries depending arms 69 in which are mounted short shafts carrying at one end a socket 70 and at the other end a gear 71 arranged to be engaged and driven by a gear 72 mounted on the shaft 64. From this construction it will be manifest that the shield 68 may swing about the shaft 64 and the mesh of the gears 71, 72 will always be maintained. A suitable and convenient form of tool 73 is provided for forming holes or incisions in the wall of the material above the under-cut. The shanks of the tools are arranged to be detachably secured in the sockets 70 in any suitable manner. With this arrangement, when the machine is advanced to its work, the tools 73 operate to form openings or incisions for receiving breaking down means to dislodge particles of the wall at the same time that the side and under-cuts are made. When a sufficient depth of cut has been made and it is desired to break down the body of the under-cut coal, the tools 73 are released with respect to the sockets and removed therefrom so that they may be withdrawn by hand without withdrawing the entire machine and when thus withdrawn the breaking down means may operate in these holes or incisions. The shield 68 may be swung about its pivot until the face of the shield is presented toward the holes or incisions formed by the tools 73, so that the driving or operating mechanism of the tools may be protected. Thus it will be apparent that the breaking down will be effected without the loss of time incident to the withdrawal of the entire machine as the tools 73 may be readily detached.

In the operation of machines of this character and especially mining machines, as heretofore carried out and wherein provision has not been made for automatically removing the material when broken down, operators remove the broken down material which has fallen upon the floor, either by hand or else manually by shovels before the machine can again be advanced to its work. This has always consumed valuable time, which might otherwise be employed in effecting another cut preparatory to breaking down more material. It is one of the objects of the present invention to provide means whereby this time may be saved and

wherein instead of removing the broken down material by hand, this work may be accomplished without in the least interfering with the continuous action of the machine in making the next cut. A simple and efficient means for accomplishing these ends and objects will now be described.

The frame 47 upon which the cutter 48 operates, is arranged in the form of a platform, as clearly indicated in the drawings, and receives the material which is detached or broken down. As this platform is carried by the machine it will be readily seen that no obstruction is offered impeding the progress of the machine as it is advanced to the next cut. The detached particles falling upon the platform 47 may be removed therefrom in the following manner: Mounted upon the frame 15 is a supplemental or carrier frame 74 which, for the sake of convenience, will be hereinafter designated as a jib, reference being had more particularly to Figs. 1, 2 and 3. Suitably mounted on the jib 74 at the front end thereof, is a scoop or shovel 75 having the toe or forward end thereof presented forwardly and arranged to gather or scoop up the material from the platform 47 and remove the same. This scoop or shovel may be operated in any suitable manner, but a simple and efficient means for accomplishing this end will now be described. In the form shown the scoop or shovel 75 is pivotally mounted on horizontal gudgeons or pintles or the like, as indicated at 76 whereby the said scoop may be rocked about a horizontal axis as indicated in dotted lines in Fig. 2, to dump the material out of the rear end thereof after it has been scooped up thereby. The scoop shovel may be tilted in any suitable manner, preferably by means of gearing which will now be described, particular reference being had to Figs. 1 and 3.

One of the gears of the train of gears 30 is mounted on a shaft 77 suitably journaled in the frame work. This shaft 77 is preferably a short shaft and is flexibly connected in any ordinary and well known manner with a hollow shaft 78 as indicated at 79 and is provided with suitable bearings 80, preferably secured to the trough or way 81. The flexible connection 79 permits the jib to turn about its upright axis 82, as will be hereinafter set forth. Arranged within the hollow shaft 78 to slide longitudinally therein but adapted to rotate therewith is a shaft 83 carrying loosely upon the forward end thereof a pair of oppositely faced bevel gears 84, 85, either of which may be clutched to rotate with the said shaft at will in any suitable or well known manner as by means of an ordinary form of clutch 86. A bevel gear 87, is arranged to intermesh with and be driven by the gears 84, 85. This gear 87 is mounted on and for rotation with the

5 axle or pivot 76 of the shovel or scoop 75 so that when one or the other of the gears 84, 85, is clutched to rotate with the shaft 83, the scoop or shovel will be tilted or 55 swung about its pivot or axle to elevate the forward end thereof.

It is also necessary that the scoop or shovel be advanced and retracted independently of the machine in order that the detached or broken down material may be 10 scooped up. A simple and efficient means for effecting this movement of the scoop or shovel will now be described. The pintles 76 upon which the scoop or shovel 15 is mounted and which form its axis, are mounted in a forked frame comprising arms 88, mounted to slide longitudinally in housings or guides 89. The arms of this frame are provided with rack teeth as 20 clearly indicated in Fig. 2 with which gears 90 mounted on a shaft 91 mesh, and this shaft 91 is journaled in suitable supports upon the jib 74. Thus when the shaft 91 is rotated in one direction or the other, the 25 arms 88 or forked support of the scoop may be moved forwardly and backwardly, longitudinally carrying with them the scoop 75, and hence it will be seen that the scoop will be advanced to scoop up the material 30 from the platform 47 and then withdrawn to the point where the dumping is to be made. The longitudinal movement of the shaft 83 with respect to the hollow shaft 78 permits the gearing for tilting the scoop 35 to remain in mesh during such movements of the scoop, as will be readily understood. The rotation of the shaft 91 in either direction may be effected in any suitable manner, and at will; and for this purpose the 40 hollow shaft 78 may be provided with a gear 92 arranged to engage and drive a companion gear 93, mounted upon a shaft 94, journaled upon the jib 74. Loosely mounted on the shaft 94 are oppositely arranged bevel gears 95, 96, and a clutch 97 of 45 any ordinary and well known construction may be employed for locking either of the gears 95, 96, for rotation with the shaft 94. A bevel gear 98 is mounted on the shaft 50 91 and is arranged to intermesh with the gears 95, 96. Thus it will be manifest that the shaft 91 may be revolved in either direction at will to advance the shovel to scoop up the material or retract it after the material 55 is scooped up, to the point where the dumping is to be made.

It is also desirable that the scoop shall be mounted so as to move transversely across the machine in order that the entire width 60 of the room or a considerable area may be commanded thereby, to the end that all of the material may be scooped up and loaded into the vehicle or receptacle. For this purpose, the scoop may be mounted in any desired or suitable manner but preferably the

jib 74 is mounted to swing upon the upright pivot 82 already described. A bearing 99 (see Figs. 1 and 2) is carried by the jib and is arranged to engage a bearing flange 100 carried by the main frame, where 70 by the thrust of the scoop or shovel advancing mechanism is resisted, and the jib is guided in its swinging movement. For the same purpose a bearing 101 is provided upon the main frame upon which the forward end of the jib bears, in order to steady and guide the latter in its movements. If 75 desired and as shown the bearings 99, 101, may be anti-friction rolls in order to reduce friction. The swinging movement of 80 the jib about its upright pivot 82 may be effected in any desired or suitable manner, and a simple and efficient means for accomplishing this result will now be described, reference being had particularly to Figs. 1 85 and 3.

A segment rack bar 102, suitably mounted upon the jib 74 is arranged to be engaged by a gear 103, which latter is also provided with gear teeth so positioned that they will 90 intermesh with operating gears 104, 105, loosely mounted on the shaft 94. Any ordinary, suitable form of clutch 106 is provided for coupling either of the gears 104, 105 to the shaft 94, whereby the gear 103 95 may be rotated in either direction at will, and hence the jib 74 may be swung or moved in either direction at will, thereby enabling the shovel or scoop 75 to command the entire or any portion of the area of the room. 100

In order to obtain the highest degree of efficiency and speed in operating this machine, it is important that the work of loading the material into the receptacles or vehicles to carry it away, be carried on concurrently and simultaneously with the operation of the machine. In the arrangement, as above described, this can be most conveniently and expeditiously effected by arranging the shovel or scoop to deliver the 110 material therefrom into the receptacle or vehicle. To this end, therefore, there is provided upon the jib 74 the trough or way 81 which is upwardly inclined from the forward end thereof, said forward end being 115 so relatively arranged with respect to the scoop or shovel 75, that when the forward end of the latter is elevated or tilted as above described, the material will run by gravity from the scoop or shovel onto a conveyor 107, which latter is preferably of the endless type (see particularly Fig. 2). The other end of the trough or way 81 and the respective end of the conveyor 107 are arranged in suitable positions to deliver into 125 a car 108 the material which is deposited upon the conveyor 107 from the shovel or scoop 75. This endless conveyor 107 is operated, in the present form of the invention by means of a shaft 109 arranged prefer- 130

ably at the lower end thereof and a shaft 110 is arranged at the other end of the conveyer over which the latter passes. The shaft 109 is rotated through the medium 5 of a gear 111 thereon (reference being now had more particularly to Fig. 3) which meshes with a gear 112 on a shaft 113, the latter being mounted upon the jib and is arranged to receive rotation through the en- 10 gagement of a gear 114 secured for rotation with the gear 112 and which gear 114 meshes with a gear 115 on the shaft 94. A suitable or any ordinary form of clutch 116 may be employed to lock or unlock the gear 115 15 with respect to the shaft 94, whereby the actuation of the conveyer 107 may be started or arrested at will.

In Figs. 6 and 7 there is shown a modified form and arrangement for effecting a 20 loading of the material from the scoop or shovel to the receptacle which conveys away the material. In this form the trough or way 117 is arranged horizontally and the scoop or shovel 118 is arranged to slide 25 longitudinally with respect to the trough or way 117 and the trough or way is adapted to swing about the upright pivot 119. The car or receptacle 120 is arranged at the end of the trough or way 117 so as to 30 receive the material discharged from the latter. A rack bar 121 is mounted upon the jib preferably some distance above the bottom of the trough or way 117 and pivotally mounted at the forward end of the 35 rack bar 121 is an ejector 122. The scoop or shovel 118 in this form of the invention is pivotally connected as at 123 to the arms 124 which latter are preferably arranged below and spaced from the rack bar 121 40 and are provided with rack teeth 125 on the upper faces thereof. A shaft 126 corresponding with the shaft 91 is mounted upon the jib and receives its motion similar to the manner in which the shaft 91 is ro- 45 tated. The gears 127 are provided on the shaft 126 which engages the rack teeth 125 and serves as a means for moving the arms 124 forwardly and rearwardly to correspondingly advance or retract the scoop or shovel 50 118. Another gear 128 is provided on the shaft 126 and this gear 128 meshes with the teeth on the rack bar 121, the latter being preferably arranged intermediately of arms 124. Thus it will be manifest that 55 when the shaft is rotated the scoop or shovel 118 will not only be moved forwardly or backwardly but the rack bar 121 will also be moved in a direction opposed to the direction of movement of the 60 scoop or shovel to correspondingly move the ejector 122, which latter removes the material from the scoop or shovel into the trough or way 117.

Any suitable convenient arrangement of 65 gearing for positively swinging the ejector

122 at will may be provided but as the invention does not reside in the specific form and arrangement of such gearing, it is thought that illustration of such gearing is not necessary. In this form of arrangement when 70 the scoop or shovel 118 has been advanced to scoop up a load of the material from the platform 47 and has been retracted to the point shown in full lines in Fig. 7, the ejector 122 will then be lowered to the position shown in full lines in said figure and the gears 127 will then be actuated to advance the scoop or shovel to scoop up another load of material. Simultaneously with such movement the rack bar 121 will 75 be moved in the opposite direction and will force the material backwardly into the trough or way 117. This ejector 122 not only prevents the material from being advanced with the scoop or shovel by acting 80 as a stop or scraper, but also sweeps the material rearwardly through the trough or way 117 and into the car or receptacle 120. In this form of the invention the scoop is open-ended and the material is loaded into 85 the car or receptacle 120 through one side of the latter as clearly indicated. This form of arrangement is particularly well adapted for operation in mines and especially in thin or shallow veins of material 90 or coal where a particularly low framework is necessary.

In the form of machine where the under-cut or kerf is made with a chain cutter, it is desirable to snub or cut off or break down 100 the lower corner of the under-cut material, in order that when breaking down mechanism actuates in the holes or incisions made above the under-cut, the material will have sufficient room to fall and properly disintegrate. Heretofore this last operation has been performed by hand. In such case it was necessary to first withdraw the machine from the material it was operating upon in order to give proper access to the 110 wall of the material. In the present invention there is provided means whereby this snubbing, cutting off, or breaking down of the material may be accomplished automatically and during the operation of the 115 apparatus. A suitable and efficient mechanism for accomplishing this end will now be described, and preferably comprises one or more cutters 129 adapted to be detachably bolted or fastened to the scoop or shovel 120 75 so as to be projected beyond the forward edge thereof. At the proper time of such operation upon the wall of the material, the cutters 129 may be adjusted in position upon the scoop or shovel to project forwardly 125 therefrom. The scoop or shovel is then advanced in the manner as has already been set forth and this cutting, snubbing or breaking down is effected in the manner as clearly indicated in Fig. 8 of the drawings 130

and without withdrawing the machine from the material. After this cutting operation, the scoop or shovel may be withdrawn in the manner as already set forth and the cutters 5 129 unfastened and adjusted into inoperating positions preferably back into the floor of the scoop or shovel, as clearly indicated in Fig. 3. It will be understood that this cutting with the cutters 129 requires the expenditure of but a small amount of power 10 and can be readily and easily applied through the scoop or shovel advancing means.

In the event that an electric motor 17 is 15 employed for operating the several parts of the machine, as above described, it is necessary to supply the operating current thereto in a manner that will permit of the advancement of the machine farther and farther toward the work as the material is broken down, and a simple and efficient means for accomplishing this result comprises the conductor 118 which leads from the motor 17 (see particularly Fig. 2) to a reel 130 suitably mounted to rotate upon the main frame. 20 A flexible conductor 131 is arranged to be wound upon the reel 132 or to be unwound therefrom as the case may be, and electrical connection, in any suitable or well known manner as will be fully understood by persons skilled in the art, may be made from the conductor 131 to the reel 130, and from said reel to the conductor 18, whereby current 25 may be supplied to the motor 17. Obviously, the conductors 131 and 18 are of the ordinary type of insulated conductors, whereby short circuiting is prevented. By providing means for winding or unwinding the conductor 131 from the reel 130 synchronously with the advancing or retracting movements of the machine, the current is supplied to the motor for actuating the several parts of the apparatus as above explained. The reel 130 may be conveniently 40 rotated in the following manner: A gear 132 mounted on the axle of the reel 130 engages and is driven by a worm 133 mounted on the shaft 32. From this construction and arrangement it will be manifest that when the 45 motor 17 is actuated in one direction or the other, the conductor 131 will be correspondingly reeled up or paid out.

In order to carry out the general system of conveying away the material, it is desirable 50 to provide means for the automatic withdrawal of the loaded cars or vehicles 108 and the co-incident advancement of empty cars from and to the point where the material is delivered by the delivery device above described. A simple and efficient means for accomplishing this result comprises tracks 134 upon which the cars 108 run. The tracks are shown as arranged 60 similar to a turn out in a street car line upon one branch of which the empty cars are run

and upon another part of which the loaded cars are run, it being understood that in the general operation of a system of this character, when the machine is operating in a mine, a mine locomotive will be employed to 70 run a train of empty cars down the mine tracks to a particular room in which the machine is at work, and thence onto the side or turn-out track and then remove from the other branch of the side or turn-out track 75 the loaded cars. Automatic means whereby the cars are removed as fast as they are loaded so that they may be temporarily moved to one side of the switch or turn-out and an empty car advanced to take its place 80 will now be described, and comprises an endless belt or cable 135 suitably mounted upon guide pulleys 136, 137, 138, 139, conveniently arranged, and these cars are adapted to be attached to the runs of the cable by means of 85 fastening devices 104 connected with the cars and which fastening devices may be readily detached when desired. The endless cable is given motion in any suitable manner, preferably from the pulley 139 on the shaft 90 of which is secured a gear 141 which latter is adapted to be engaged by a gear 142 driven through suitable gearing 143 from the axle of the motor 17, and a clutch 144 may be employed for controlling the rotation of 95 the shaft on which the gear 142 is mounted.

The present divisional application contemplates the omission of the cutting apparatus and also of the platform 47 and the drilling mechanism so that the machine 100 shown in the drawings can be used purely as a loading machine in a narrow entry for operation at the base of the mine wall in a low roof mine chamber. The fact that the scoop has a rear end portion approximately of the same width as the endless belt conveyer and is in direct alignment therewith and can reach out in front of the conveyer enables the width of the machine to be greatly reduced. It should also be observed that the motor may be placed on the main frame beneath the conveyer so as to maintain a narrow machine when used 105 as a loader only.

The jib frame is mounted on an upright 110 axis 82 which is preferably nearer the delivery end of the conveyer than the receiving end so that the scoop may move through relatively larger arcs than the delivery end of the conveyer. This arrangement will 115 maintain the delivery end of the conveyer over the mine car for various arcuate positions of the scoop.

The wheeled truck comprises the wheels 120 16 and the main frame, and the propelling mechanism for this truck comprises the shaft 21 and the sprocket chains 23 and the worm gearing therefor may be such as to move the loader forward or rearward at 125 any desired speed. The gearing may be 130

such as to move the scoop forward slowly but if the scoop meets with too much resistance there may be slipping of the wheels on the track and therefore in some instances it may be desirable to move the loader forwardly even more slowly and more powerfully by means of the spaced apart screw-threaded rods anchored in the mine chamber close to the sides of the jib frame but allowing sufficient room for the latter to swing over its arcuate paths of travel.

An important feature of my invention is the provision of a pivoted rear portion of the scoop and approximately horizontal reciprocation of the pivoted rear portion of the scoop. In the present instance this is secured by securing the scoop to a supporting shaft or trunnions 76 which are pivoted in the slide blocks 88 and which in turn are confined to approximately horizontal guideways in the jib frame. The operating mechanism may therefore be such that the rear portion of the scoop itself may be reciprocated in a general horizontal direction while the forward portion is given turning movements to cause the material gathered by the scoop to slide to the rear portion of the scoop and finally out of such rear portion backwardly onto the endless belt conveyer.

It should also be understood that the detachable platform 47 may be secured to the main frame without the use of any of the cutting apparatus. A metal platform is thus employed instead of using the floor of the mine chamber as a platform. However the apparatus still remains a loading machine.

Obviously those skilled in the art may make various changes in the details and arrangement of parts without departing from the spirit and the scope of my invention as defined by the claims hereto appended, and I wish, therefore, not to be restricted to the precise construction herein disclosed.

Near the lower end of the endless conveyer may be located the cross piece 75 inclined downwardly and rearwardly toward the upper surface of the endless conveyer so that said cross piece may coöperate with the spaced-apart side plates to act as a chute to direct material from the rear end of the scoop onto the said conveyer, and said cross piece may also act to prevent the material discharged from the scoop from falling off the conveyer. The conveyer is continuously operated so as to be capable of conveying the discharged material to the mine car as soon as such material is received by the conveyer.

What is claimed as new is:—

1. In a loading machine, the combination with guideways extending forward and rearward, an endless conveyer extending for-

wardly between said guideways, supporting mechanism confined in said guideways, a scoop body pivotally connected at its rear end directly to said supporting mechanism, means for effecting the movement of said supporting mechanism backward and the turning said scoop relatively to said supporting mechanism, to enable said scoop to take a load and discharge it out of the rear end thereof near such point of pivotal connection onto said conveyer.

2. In a loading machine, the combination with a narrow truck frame mounted on wheels adapted to enter a narrow entry in a mine, of an endless conveyer extending from the forward end of said frame longitudinally thereof to the rear, a scoop mounted at the forward end of said frame an advance thereof and in advance of said conveyer and in alinement therewith, and powerful propelling mechanism independent of said wheels and comprising a rod extending longitudinally of said frame and adapted to engage at one end an abutment spaced from said frame in the mine and connected at its other end to the machine.

3. In a loading machine, the combination with a frame, of a conveyer extending from the forward end of said frame longitudinally thereof to the rear, a scoop open at both ends and pivotally mounted at the forward end of said frame in advance of said conveyer and in alinement therewith and pivoted at its rear portion for operation in a low-roofed mine chamber, a toothed gear fixed to the said scoop at its pivot and means for operating said scoop to take a load and deliver it out of its rear end onto said conveyer, said operating means including said toothed gear.

4. In loading apparatus, the combination with a truck frame, propelling mechanism connected to the wheels of said truck frame and depending upon frictional contact of the treads of said wheels for propelling effect, an endless conveyer mounted longitudinally on said truck frame with its forward end extending to a position near the floor of a mine chamber, a scoop at the forward end of said conveyer in advance of said frame, additional propelling mechanism connected to anchoring means in the mine for moving said truck frame forward more powerfully than said first named propelling mechanism to push the scoop under loose material in front of said frame to direct such material to the receiving end of said conveyer, and means for operating said conveyer to take the said material toward loading position.

5. In loading apparatus, the combination with a wheel-mounted frame having a free and unobstructed space back of the same for movement of mine cars, of propelling mechanism connected to said wheels, means for controlling said propelling mechanism at

105

95

100

110

115

120

125

130

will, conveyer mechanism mounted on said frame and extending longitudinally thereof from a receiving position at the forward end of said frame to a delivery position to a mine car back of said frame, a scoop connected to said frame for free and unobstructed movements in advance thereof, another propelling mechanism mounted on the machine and adapted to be connected to an anchor in the mine for moving said scoop to force it under material to be loaded, and means for controlling said second-named propelling mechanism at will.

6. In loading apparatus, the combination with a scoop, of supporting mechanism immovably secured to said scoop rearward of its front end, power driven means whose sole connection to said scoop is directly to said supporting mechanism for shifting said supporting mechanism forwardly and rearwardly to effect bodily forward and backward movements of said scoop and to transmit turning movements to said supporting mechanism to effect arcuate turning movements of the forward portion of said scoop, conveyer mechanism behind said scoop for receiving the load gathered and discharged to said conducting mechanism by such movements of said scoop, and a supporting frame for carrying the aforesaid parts in coöperative relation.

7. In a machine of the nature described, a frame, guide-ways extending forward and rearward of said frame, slide-blocks confined in said guide-ways, conducting mechanism on said frame behind said blocks, a scoop pivoted directly to said slide-blocks rearward of its front portion, and mechanism for moving said slide-blocks forward and backward and turning said scoop in said blocks, substantially as described.

8. In loading apparatus, the combination with a portable truck, of power mechanism for propelling said truck forward, a conveyer mounted on said truck and extending from the front toward the rear, a scoop for delivering material to said conveyer from a position forward of said truck, and additional propelling mechanism connected to said truck to act as a rigid abutment against rearward movement and acting to move the same forward more powerfully than said first-named propelling mechanism to effect forcible movement of said scoop into a pile of material or under material in a pile.

9. In loading apparatus, the combination with a wheel-mounted vehicle, of propelling mechanism connected to one or more of the wheels of said vehicle, for transporting said vehicle forwardly and rearwardly, an endless belt conveyer mounted on said vehicle and extending from a low position at the front end of said vehicle on an incline longitudinally to a higher position toward the rear of said vehicle, a scoop mounted on

said vehicle in advance of said conveyer and in alinement therewith for delivery of material to said conveyer, and additional propelling mechanism comprising a pair of anchored screw-threaded rods spaced apart and extending longitudinally to move said vehicle forward more powerfully than said first named propelling mechanism to force said scoop under material to obtain a load.

10. In loading apparatus, the combination with a frame, of a scoop, conveyer mechanism mounted on said frame longitudinally thereof behind said scoop and in alinement therewith, driving mechanism for moving the scoop forward and rearward with its receiving lip resting on the ground by gravity, mechanism for limiting the reciprocation of the rear portion of said scoop over an approximately horizontal path, and another driving mechanism for tilting the front portion of said scoop to cause material therein to slide out of the rear end thereof for delivery to said conveyer.

11. In loading apparatus, the combination with a scoop, of mechanism confining the rear portion of said scoop to movements in a general horizontal direction and to turning movements, a laterally movable support for said scoop, a conveyer on said support and behind said scoop, driving mechanism for moving the scoop forward and rearward by reciprocating the rear portion thereof in a general horizontal direction along said confining mechanism, another driving mechanism for tilting the forward portion of said scoop about a pivot at such confining mechanism to effect the discharge of the load therein out of the rear end of said scoop onto said conveyer, and mechanism for moving the machine forward.

12. In loading apparatus, the combination with a frame, of a scoop, a conveyer on said frame behind said scoop, mechanism for confining the rear portion of said scoop to a rearward and forward movement over an approximately horizontal path, driving mechanism for moving said scoop bodily forward and rearward, additional driving mechanism for turning said scoop on an axis substantially at said path of reciprocation of the rear portion of said scoop, and means for controlling at will either of said driving mechanisms independently of the other.

13. In a loading machine, the combination with a portable frame mounted on a plurality of pairs of wheels having transverse pairs of axes, one for each of said pairs, of a supplemental frame pivotally connected to said main frame for lateral adjustment relatively thereto, endless conveyer mechanism extending longitudinally of said supplemental frame from a forward receiving position toward the rear through the space between the wheels on one of said axes, said conveyer mechanism being inclined up.

- wardly at an angle with the horizontal so as to occupy a position nearer a horizontal position than a vertical position, a scoop pivotally connected to said supplemental frame 5 to move laterally therewith and confined against lateral movement relatively to said conveyer mechanism, such pivotal connection between said scoop and said supplemental frame enabling the forward lip of 10 said scoop to be moved up and down on a horizontal transverse axis, such movement being limited to arcs less than a complete circle, said scoop being connected to said supplemental frame to extend in advance 15 thereof with the forward end of said conveyer occupying a position back of the forward receiving lip of said scoop and approximately in front of the transverse axes of said wheels, the said scoop lip being always horizontally in advance of said frames 20 when in scooping position and always horizontally in advance of the receiving end of said conveyer when in scooping position, the forward end of said conveyer always extending to a horizontal plane below the axes 25 of said wheels when said scoop is scooping material in a plane below the axes of said wheels, and means for operating said scoop and said conveyer to gather material horizontally in advance of said frames in various 30 arcuate positions of said scoop and transfer such material longitudinally of said supplemental and main frames rearwardly toward loading position.
14. In a loading machine, the combination with a main frame mounted on wheels having a plurality of transverse parallel axes, of a supplemental frame pivoted on an upright axis on said main frame for lateral adjustment relatively to said main frame, an endless conveyer having superposed portions traveling in opposite directions and mounted on said supplemental frame and longitudinally thereof on transverse end axes, said 40 conveyer extending from the forward axis near the receiving position on an upward incline nearer the horizontal than the vertical, the lower axis of said conveyer being located in a horizontal plane below the axes 45 of said wheels, a scoop having its forward receiving lip substantially parallel with the lower axis of said conveyer and always in advance of said frame in a general horizontal direction when in scooping position and 50 always in advance of said conveyer when in scooping position, the said scoop being mounted on said supplemental frame to move laterally therewith and confined against lateral movement relatively to said conveyer, the forward lip of said scoop being movable up and down on a horizontal transverse axis, such movement being limited to arcs less than a complete circle, means for operating said scoop and conveyer to gather material in advance of said frames and
- transfer such material longitudinally of said frames rearwardly toward loading position, and propelling mechanism comprising a rod parallel to the length of the machine and connected between said main frame and an 70 abutment for moving the machine forward independently of said wheels.
15. In a loading machine, the combination with a main frame mounted on wheels having a plurality of transverse parallel axes, 75 of a supplemental frame pivoted on an upright axis on said main frame for lateral adjustment relatively to said main frame, an endless conveyer having superposed portions traveling in opposite directions and mounted 80 on said supplemental frame and longitudinally thereof on transverse end axes, said conveyer extending from the forward axis near the receiving position on an upward incline nearer the horizontal than the vertical, the lower axis of said conveyer being located on said supplemental frame in a horizontal plane below either of the axes of said wheels, a scoop having its forward receiving lip substantially parallel with the 85 lower axis of said conveyer and always in advance thereof when in scooping position and always in advance of said frames when in scooping position, said scoop being mounted on said supplemental frame to move laterally therewith and confined against lateral movement relatively to said conveyer, the forward receiving lip of said scoop being movable up and down on a horizontal transverse axis, such movement being 90 limited to arcs less than a complete circle, means for operating said conveyer to transfer material longitudinally of said frame rearwardly toward loading position, propelling mechanism connected to the said 95 wheels, and additional propelling mechanism independent of said wheels and comprising a longitudinal rod connected between said main frame and an abutment in the mine.
16. In a loading machine, the combination with a portable frame mounted on wheels having a plurality of transverse axes, of a supplemental frame pivotally connected to said main frame for lateral movement relatively thereto, endless conveyer mechanism extending longitudinally of said supplemental frame from a forward receiving position toward the rear, said conveyer mechanism being inclined upwardly at an angle 100 with the horizontal so as to occupy a position nearer a horizontal position than a vertical position and having its forward end always in a horizontal plane below the axes of said wheels when in receiving position, a scoop pivotally connected to said supplemental frame to move laterally therewith and confined against lateral movement relatively to said conveyer mechanism, such pivotal connection between said scoop and said 105
- 110
- 115
- 120
- 125

- supplemental frame enabling the receiving lip of said scoop to be moved up and down on a horizontal transverse axis, such movement being limited to arcs less than a complete circle, said scoop being connected to said supplemental frame so as to always extend in advance of said main and supplemental frames when in receiving position, propelling mechanism connected to the wheels, means for controlling the operation of said propelling mechanism at will, additional propelling mechanism carried by the machine and operating independently of the wheels and adapted to be connected between the main frame and an anchor in the mine to force said scoop under material to be loaded, and means for controlling the operation of said additional propelling mechanism.
17. In a loading machine, the combination with a portable frame mounted on wheels having a plurality of transverse axes, of a supplemental frame pivotally connected to said main frame for lateral adjustment relatively thereto, endless conveyer mechanism extending longitudinally of said supplemental frame from a forward receiving position toward the rear, said conveyer mechanism being inclined upwardly at an angle with the horizontal so as to occupy a position nearer a horizontal position than a vertical position, a scoop pivotally connected to said supplemental frame to move laterally therewith and confined against lateral movement relatively to said conveyer mechanism, such pivotal connection between said scoop and said supplemental frame enabling the receiving lip of said scoop to be moved up and down on a horizontal transverse axis, said scoop being connected to said supplemental frame to extend in advance thereof with the forward end of said conveyer mechanism occupying a position back of the forward receiving lip of said scoop and approximately in front of the transverse axes of said wheels, said scoop lip being always horizontally in advance of said frames when in scooping position and always horizontally in advance of the receiving end of said conveyer mechanism when in scooping position, the forward end of said conveyer mechanism always extending to a horizontal plane below the axes of said wheels, and propelling mechanism independent of said wheels and comprising a longitudinal rod connected between the machine and an abutment in the mine for moving the machine forward.
18. The combination with a vehicle, of an endless conveyer mounted thereon, a pivotally mounted scoop located in advance of and adjacent to said conveyer, means for tipping said scoop rearwardly upon its pivotal connections to discharge its contents upon
- said conveyer, and cutting members carried by the scoop, said cutting members being adapted to be adjusted with relation to the forward edge of the scoop.
19. A scoop or bucket, and cutting members carried thereby and adjustable with respect thereto.
20. In a loading machine, the combination with a frame, of a scoop having a turning axis confined to positions along general horizontal directions, a conveyer on said frame behind said scoop, means for moving said scoop bodily forward and rearward relatively to said frame and parallel to the length of the machine and in alinement with said conveyer by remaining in front thereof, mechanism for tilting said scoop upwardly to discharge the load out of the rear end thereof onto said conveyer, and mechanism for lowering said scoop by positively moving it and preventing it from dropping by gravity.
21. In a loading machine, the combination with a scoop, of a laterally movable support for said scoop, a conveyer behind said scoop, means for moving said scoop bodily forward and rearward parallel to the length of the machine, an oppositely disposed clutch for controlling at will the starting, stopping or reversing of such forward and rearward movements, mechanism for moving the front portion of the scoop upward and downward, and an additional oppositely disposed clutch for controlling at will the starting, stopping and reversing of such upward and downward movements.
22. In a loading machine, the combination with a frame, of a scoop having a turning axis at its rear end confined to a generally horizontal path of movement, a conveyer on said frame behind said scoop, means for moving the scoop bodily forward and rearward parallel to the length of the machine and relatively to said frame to get a load, and mechanism for swinging the front portion of said scoop on such axis substantially at the rear portion of said scoop to deliver its load rearwardly to said conveyer.
23. In a loading machine, the combination with a portable truck, of a scoop having a turning axis confined to a generally horizontal path of movement, a conveyer on said truck behind said scoop, driving mechanism for moving said scoop forward and rearward relatively to said conveyer to reach out for a load and bring it back to a position near the receiving end of said conveyer, and means for turning said scoop on such axis to discharge material from said scoop onto said conveyer.
24. In a loading machine, the combination with a portable frame mounted on wheels having a plurality of transverse axes, of a supplemental frame pivotally connected to said main frame for lateral adjust-

ment relatively thereto, endless conveyer mechanism extending longitudinally of said supplemental frame from a forward receiving position toward the rear, said conveyer mechanism being inclined upwardly at an angle with the horizontal so as to occupy a position nearer a horizontal position than a vertical position, a scoop pivotally connected to said supplemental frame to move laterally therewith and confined against lateral movement relatively to said conveyer mechanism, such pivotal connection between said scoop and said supplemental frame enabling the forward lip of said scoop to be moved up and down on a horizontal transverse axis, such scoop being connected to said supplemental frame to extend in advance thereof with the forward end of said conveyer mechanism occupying a position back of the forward receiving lip of said scoop and approximately in front of the transverse axes of said wheels, said scoop lip being always horizontally in advance of said frames when in scooping position and always horizontally in advance of the receiving end of said conveyer mechanism when in scooping position, propelling mechanism connected to the said wheels, the forward end of said conveyer mechanism always extending to a horizontal plane below the axes of said wheels when said scoop is scooping material in a plane below the axes of said wheels, and additional propelling mechanism comprising a longitudinal rod connected between said frame and an abutment in the mine for moving the machine forward more powerfully than the propelling mechanism connected to the wheels.

25. In a loading machine, the combination with a portable truck, of a jib mounted on said truck for arcuate movement on an upright axis, a conveyer mounted on said jib, a scoop in advance of said conveyer and supported by said jib in alinement with said conveyer and movable in an arc therewith, mechanism for confining the turning axis of said scoop to a generally horizontal path of movement, a motor on said portable truck, and operating connections between said motor and said conveyer and said scoop for operating said conveyer and said scoop in the various positions of said jib.

26. In a loading machine, the combination with a scoop, of mechanism for pivotally supporting said scoop, a stationary supporting frame confining the turning axis of said scoop to a generally horizontal path of movement, conveying mechanism on said frame behind and near the scoop and means for imparting to the forward portion of the scoop an upright movement, and to the rear portion an approximately reciprocatory movement relatively to said frame, such means causing the forward portion of the scoop to go forward low enough to take a

load and such means causing said scoop to be turned on its rear pivoted portion to discharge the load backward therefrom for delivery onto the top of the receiving end of said conveying mechanism.

70

27. In a loading machine, the combination with a frame, of a scoop having a turning axis confined to a generally horizontal path of movement, conveyer mechanism on said frame behind said scoop extending to a receiving position horizontally back of such restricted path, and means for effecting forward and backward reciprocating horizontal movements of the rear portion of said scoop and also partial rotating movements of said scoop, whereby such reciprocating and partial rotating movements co-operate to enable said scoop to take a load and discharge it onto said conveyer mechanism.

80

85

28. In loading apparatus, the combination with a main frame mounted on wheels having a plurality of transverse parallel axes, of a supplemental frame pivoted on an upright axis on said main frame for lateral adjustment relatively to said main frame, an endless conveyer having superposed portions traveling in opposite directions and mounted on said supplemental frame longitudinally thereof on transverse end axes, said conveyer extending from the forward axis near the receiving position on an upward incline nearer the horizontal than the vertical, the lower axis of said conveyer being located in a horizontal plane below the axes of said wheels, a scoop having its forward receiving lip substantially parallel with the lower axis of said conveyer and always in advance of said frame in a general horizontal direction when in scooping position and always in advance of said conveyer when in scooping position, the said scoop being mounted on said supplemental frame to move laterally therewith and confined against lateral movement relatively to said conveyer, the forward lip of said scoop being movable up and down on a horizontal transverse axis, such movement being limited to arcs less than a complete circle, and means for operating said scoop and conveyer to gather material in advance of said frames and transfer such material longitudinally of said frames rearwardly toward loading position.

29. In a loading machine, the combination with a main frame mounted on a plurality of pairs of wheels having a plurality of transverse parallel axes, of a supplemental frame pivoted on an upright axis on said main frame, for lateral adjustment relatively to said main frame, an endless conveyer having superposed portions traveling in opposite directions and mounted on said supplemental frame and longitudinally thereof on transverse end axes, said conveyer extending from the forward axis near the re-

120

125

130

- ceiving position on an upward incline nearer the horizontal than the vertical, the lower axis of said conveyer being located in a horizontal plane below all of the axes of said wheels when in receiving position, a scoop having its forward receiving lip substantially parallel with the lower axes of said conveyer and always in advance thereof when in scooping position and always in advance of said frames when in scooping position, said scoop being mounted on said supplemental frame to move laterally therewith and confined against lateral movement relatively to said conveyer, the forward receiving lip of said scoop being movable up and down on a horizontal transverse axis, such movement being limited to arcs less than a complete circle, means for operating said conveyer to transfer material longitudinally of said frame rearwardly toward loading position, propelling mechanism connected to the said wheels, and additional propelling mechanism independent of said wheels and adapted to be connected between the machine and an anchor in the mine.
30. In a loading machine, the combination with spaced-apart guideways extending forwardly and rearwardly, of an endless belt conveyer between said guideways, slide blocks confined in said guideways, a scoop pivotally connected to the forward ends of said slide blocks at the rearward portion of said scoop, means for reciprocating said slide blocks in a general horizontal direction, and mechanism for turning said scoop to discharge the contents thereof onto said conveyer mechanism.
31. In a loading machine, the combination with a frame, of an endless conveyer mounted thereon and extending longitudinally thereof, a scoop combined to positions always horizontally in front of said conveyer, a reciprocable support on said frame to which said scoop is pivotally connected, means for reciprocating said support to secure forward and rearward movements of said scoop, means for independently controlling such forward and rearward movements, mechanism for turning the scoop to positively lift and to positively lower the same, and means for independently controlling such lifting and lowering movements.
32. In a loading machine, the combination with a frame, of a platform carried thereby and extending forwardly from the lower portion of said frame, a shovel pivotally connected at its rear portion to said frame, and means for operating said shovel over said platform by reciprocating the pivoted rear portion of said shovel in an approximately horizontal direction and tilting the forward portion of said shovel up and down.
33. In a loading machine, the combination with a main frame, of a platform connected to the lower forward end of said frame and carried by it, a supplemental frame pivoted on an upright axis on said main frame for arcuate movement, an endless belt conveyer on said supplemental frame and extending longitudinally thereof from a lower receiving position at the forward portion of said main frame backward toward loading position, a shovel pivoted at its rear end to said supplemental frame, and means for operating said shovel over said platform in various directions by reciprocating said rear pivoted portion of said shovel in an approximately horizontal direction and turning the forward portion in upright arcs up and down to gather a load or loads from said platform and deliver the same out of the rear end of said shovel onto said conveyer.
34. In a loading machine, the combination with framework, of a platform carried by the forward lower portion thereof near the floor of the mine chamber, means for detachably securing said platform to said framework in such position, an endless belt conveyer mounted on said framework and extending from a lower receiving position on an upward incline to a higher loading position, the scoop having its rear end pivotally mounted in front of and in alignment with said conveyer, means for reciprocating said rear end in approximately horizontal directions, and means for tilting the forward portion of said scoop to deliver its load out of the rear end thereof onto said conveyer.
